Atty's.

UNITED STATES PATENT OFFICE.

CLARENCE E. REED, OF WICHITA, KANSAS.

BOILER-TUBE CLEANER OR THE LIKE.

Application filed June 17, 1926. Serial No. 116,556.

The invention is designed to clean tubes of boilers, refinery stills and the like, of accumulated scale or carbon deposits on the interior thereof, and the invention resides in the features and combination and arrangement of parts hereinafter described and particularly pointed out in the claims.

In the accompanying drawing forming a part of the specification—

10 Figure 1 is a part side elevation, and a part longitudinal sectional view of the tool in place within a tube to be cleaned.

Figure 2 is a transverse section on the line 2—2 of Fig. 1.

15 Figure 3 is a transverse section on the line 3—3.

Figure 4 is a bottom view of the tool.

In these drawings 1 represents a rotatable head, having pockets or recesses 2 in which 20 are mounted rotary cutters 3 which incline upwardly and inwardly. These cutters are mounted on pins 4 which bear in the walls of the pockets, said pins being inserted through openings 5, and having heads 6 on

25 their outer ends to bear on the body of the head. These pins are held in place by suitable stop screws 7. The rotary cutters may be of a variety of forms, and in the form shown, a frusto-conical cutter is provided with teeth at 8 on its periphery adapted to

30 cut the carbon or scale indicated at 9. The cutters are provided also with plain faced portions 10 adapted to bear on the inner face of the tube during the cutting action. These 35 rotary cutters assume their final cutting position by centrifugal force due to the rotation of the head, the speed of which may vary from 1000 to 1800 R. P. M., and for this purpose the rotary cutter is mounted on the pin so as to have self-adjusting movement outwardly along this pin under the action of centrifugal force. Washers 11 and 12 are disposed on the pin at the sides of the rotary cutter, and it will be noticed from

40 Fig. 1 that the width of the rotary cutter is less than the distance between the opposing faces of the washers so that, as stated, the rotary cutter may assume its cutting position by centrifugal force and its plain edge or 45 face portion 10 bear against the inner face of the tube to be cleaned while the teeth 8 engage the scale 9 and cut it as the tool is rotated.

50 In rear of the head 1 there is a body 1^a having pockets 2^a in which are located fin-

ishing or burnishing rolls 3^a. These rolls may assume different forms, but they are mainly cylindrical, as shown in Fig. 1, and they are provided with teeth extending parallel with the axes of the roll, these teeth 60 being finer than the teeth of the main or advance cutters 3 so as to do finishing or polishing work on the inner surface of the tube to remove any remnants of scale which may be left after the main cutting action of the 65 cutters 3 has been performed. These finishing rolls are mounted on pins 4^a having heads 6^a at their lower ends seated in the body member, and the bore of the rolls 3^a is of 70 larger diameter than the diameter of the pins 4^a so that these finishing rolls, under the action of centrifugal force due to the rotation of the body 1^a, will set themselves out against the inner surface of the tube and perform their actions thereon.

75 This body 1^a is to be rotated through any suitable means usually employed for the operation of tube cleaners, such as a flexible shaft driven by any suitable motor, and for this purpose the body 1^a is provided with 80 an extension 1^b to which the driving shaft may be attached. The body 1^a imparts its rotary movement to the head 1 through a coupling designed to permit a certain degree of independent action between these 85 members and for this purpose the rotatable head 1 is provided with a neck 13 having a flange 14 at its end, and radially extending ribs 15 on said neck extending from the flange to the main portion of the head. As 90 shown in Fig. 3, there may be, say three of these ribs equally spaced apart and cooperating with said ribs is a sectional block or coupling member made up of the two sections 16, 16, which are externally screw threaded to engage screw threads at 17 on the interior of a cylindrical extension 18 of the body 1^a. The sectional block 16 is formed with recesses to receive the ribs 15, the 95 recesses being slightly larger than the ribs so as to permit a certain amount of play between the ribs and the block. The block is held in position by a set screw 19. A spring 100 bears at one end upon the rear face of the head 1 and at its other end upon the sectional block 16. This combination of parts provides a coupling between the finishing body 1^a and the main cutter head 1 which 105 will impart to the latter the rotary movement of the body 1^a and yet permit automati-

110

ic adjustment of the two members 1, 1^a relative to each other and to the portions of the tube upon which the respective cutters 3 and 3^a act. The coupling is in the nature of a 5 flexible one due to the construction just described. Suitable washers 21 are interposed between the ends of the finishing cutters and the body 1^a.

The tool is provided with a central bore 10 for a flushing medium, which may be air, for removing the cuttings.

It will be noticed that the terminal cutters 3 act on the end edge of the layer of scale, and not only cut and grind it away, but because 15 the direction of the pressure from the cutters is applied longitudinally of the layer said layer is broken off. This action is different from that which would take place if the pressure of the cutter was exerted against 20 the inner face of the layer of scale because in the latter event the scale would be backed up or supported by the wall of the tube and the stripping off action such as takes place with the present tool would not be accomplished.

Having thus described my invention, what I claim is:

1. In a boiler tube cleaner, the combination of a head, having pockets in its end 30 face, inclining upwardly and inwardly in relation to the axis of the apparatus, cutters mounted in said pockets having cutting surfaces to cut in a plane substantially transversely at right angles to the axis of the apparatus, said cutters being mounted on axes inclining upwardly and outwardly in respect 35 to the axis of the apparatus, said cutters having radial play under centrifugal force to set themselves outward against the tube 40 to be cleaned, substantially as described.

2. In a boiler tube cleaner, a head having pockets in its lower end, and terminal rotary toothed cutters in said pockets inclining rearwardly and inwardly relative to the axis 45 of the tool and its end face, and journal pins extending across said pockets and bearing in the wall thereof, said toothed cutters having movement outwardly along said pins under centrifugal force due to the rotation 50 of the head, said cutters maintaining the same angular relation to the axis of the tool under all conditions of use, substantially as described.

3. In a boiler tube cleaner, a rotatable 55 head, terminal rotary toothed cutters mounted in said head loosely to have outward movement from the axial center under centrifugal force, said rotary cutters each having a plain lateral bearing portion at substantially a right angle to the cutting face, to contact with the inner surface of the tube.

4. In combination in a boiler tube cleaner, a rotatable head having terminal rotary 60 toothed cutters mounted therein, said cut-

ters having their cutting faces disposed to cut in a plane substantially at right angles to the axis of the head, a finishing section composed of a body having finishing rollers mounted therein to contact with the tube 70 after being cleaned by the rotary cutters, and having their finishing faces substantially parallel with the axis of the head, a flexible driving connection between the rotatable head and the said body, and a connection for rotating said body, substantially as described.

5. In combination in a boiler tube cleaner, a rotatable head having terminal rotary toothed cutters mounted therein, said cutters 80 having their cutting faces disposed to cut in a plane substantially at right angles to the axis of the head, a body having a driving connection with the head to permit relative movement between them in a general direction transverse to the axis of the tool, finishing rollers mounted in said body loose to move outwardly under centrifugal force, and having their finishing faces substantially parallel with the axis of the head, 90 and a connection by which said body is rotated, substantially as described.

6. In combination in a boiler tube cleaning tool, a head having terminal rotary cutters inclining backwardly from the end face 95 of the head, and inwardly in relation to the axis of the tool, each cutter having its cutting face extending in a plane substantially at right angles to the axis of the tool to act on the end edge of the layer of scale and in 100 the direction of the length of said layer, each cutter being loosely mounted to set itself outwardly in respect to said axis by centrifugal force, and means for rotating 105 the tool, substantially as described.

7. In combination in a boiler tube cleaning tool, a head having terminal rotary cutters inclining backwardly from the end face of the head, and inwardly in relation to the axis of the tool, each cutter having its cutting 110 face extending in a plane substantially at right angles to the axis of the tool to act on the end edge of the layer of scale, each cutter being loosely mounted to set itself outwardly in respect to said axis 115 by centrifugal force, finishing rollers in rear of the rotary cutters, having their working surfaces parallel with the wall of the tube and loosely mounted to set themselves by centrifugal force out against the said wall 120 while maintaining their axial parallelism with the axis of said tube, and means for rotating the tool, substantially as described.

8. In combination in a boiler tube cleaning tool, a head having terminal rotary cutters inclining backwardly from the end face of the tool and inwardly in relation to the axis of the tool, each cutter having its cutting face extending in a plane substantially 125 at right angles to the axis of the tool to act 130

on the end edge of the layer of scale, each cutter being loosely mounted to set itself outwardly in respect to said axis by centrifugal force, and having a lateral contact portion 5 to engage the wall of the tube, and means for rotating the said head, substantially as described.

9. In combination in a boiler tube cleaning tool, a head having terminal rotary disc cutters on pins inclining backwardly from the end face of the tool, and outwardly in relation to the longitudinal axis of the tool, said cutters being slideable on said pins to set themselves outwardly along said pins by 15 centrifugal force, and means for rotating the head, said cutters having peripheral teeth to act on the end edge of the layer of scale, substantially as described.

10. In combination in a boiler tube cleaning tool, a head having terminal rotary disc cutters on pins inclining backwardly from the end face of the tool, and outwardly in relation to the longitudinal axis of the tool and slideable on said pins to set themselves 25 outwardly along said pins by centrifugal force, and means for rotating the head, said cutters having peripheral teeth, to act on the end edge of the layer of scale, and finishing rolls in rear of the said cutters, said 30 rolls being of cylindrical form with their axes parallel with the axis of the tool, and being mounted to set themselves out against the tube by centrifugal force, and means for rotating the tool, substantially as described.

11. In combination in a tool for cleaning tubes, a head with means for rotating the same about the axis of the tube, and terminal rotary cutters in said head mounted on pins inclining backwardly from the end face 40 of said head and outwardly relative to the longitudinal axis of the tool, said cutters being shiftable on said pins to set themselves radially outward by centrifugal force, said 45 cutters having their cutting surfaces in a plane extending transversely to the axis of

the tool, to act on the end edge of the layer of scale, substantially as described.

12. In combination in a boiler tube cleaner, a rotatable head, toothed cutters mounted therein, a body carrying finishing rollers in rear of the head and having means by which it may be rotated, and a loose driving connection between said body and head permitting relative movement of said body and head, said connection comprising 55 a neck on the head having a flange at its end, and radially extending ribs on said neck, the said body having a cylindrical extension surrounding said neck with a sectional block screw threaded therein, and 60 having grooves to receive said ribs and a spring bearing on said block and on the head, substantially as described.

13. A cleaner for boiler tubes comprising a rotatable head having rotary cutters 65 mounted therein and having cutting teeth, a body connected to said head and having rollers with finer teeth than the cutting rollers to bear on and finish the inner side of the tube, a driving connection between the head 70 and body, said body having means by which it is rotated, said finishing rollers operating in a zone of substantially the same diameter as that in which the cutters first mentioned operate.

14. In combination in a boiler tube cleaner a head, having upwardly and inwardly inclined cutters, on axes inclining upwardly and outwardly, said cutters being of conical form with the smaller diameter portion adjacent the axis of the apparatus, said cutters having teeth disposed in a plane substantially at right angles to the axis of the apparatus and said cutters having radial play under centrifugal force to set themselves 80 out against the tube being cleaned, substantially as described.

In testimony whereof, I affix my signature.

CLARENCE E. REED.
